UNITED STATES PATENT OFFICE.

ADOLPH H. LICHTER, OF TOLEDO, OHIO.

MACHINE FOR MAKING UPHOLSTERING-CUSHIONS.

1,365,041.

Specification of Letters Patent. Patented Jan. 11, 1921.

Application filed April 15, 1919. Serial No. 290,123.

To all whom it may concern:

Be it known that I, ADOLPH H. LICHTER, a citizen of the United States, and a resident of Toledo, in the county of Lucas and State 5 of Ohio, have invented a certain new and useful Machine for Making Upholstering-Cushions; and I do hereby declare the following to be a full, clear, and exact description of the invention, such as will enable 10 others skilled in the art to which it appertains to make and use the same, reference being had to the accompanying drawings, and to the characters of reference marked thereon, which form a part of this specification. 15

My invention has for its object to provide a machine whereby cushioned tops or coverings for upholstered seats or backs of automobiles, chairs, couches and the like, may be 20 rapidly made. It has for its object particularly a machine for making efficient and attractive upholstered coverings for springs used in seats and backs at a low cost of production.

25 My invention provides a means whereby the cushioned part of an automobile seat and back may be made by a gang sewing machine and whereby the parts of the cushion may be formed and secured in one operation of the sewing machine.

30 The invention may be contained in structures of different forms, inasmuch as my invention contemplates changes in details and application and form of embodiment. I 35 have selected one of such constructions and shall describe it hereinafter. The structure selected is illustrated in the accompanying drawings.

Figure 1 of the drawings illustrates a 40 front view of the gang sewing machine used in securing the parts of the cushion together. Fig. 2 is a side view of the structure containing my invention. Figs. 3, 4 and 5 illustrate perspective views showing parts broken and 45 in section to more clearly illustrate the details of construction and the mode of operation thereof. Fig. 6 illustrates a sectional view of the cushion after it has been formed in the operation of the machine containing 50 my invention.

1 indicates a gang sewing machine of the ordinary type and having a form well known in the art. It has a plurality of needles 2 that are operated by cams 5 located on a driving shaft 6 and which are driven by a suitable pulley 7. Suitable feed

mechanism is operated by the gear wheels 8 that are driven through the operation of the shaft 9 by the gear wheels 10 and 11. These form no part of my invention.

60 In front of the needles 2 is located a forming guide 12 which is mounted on a shelf 13 that may form a part of the base plate or bed plate of the machine. The guide 12 may be provided with two overhanging supporting side plates 14 which are secured to the bed plate or shelf 13. The supporting members 14 are so formed that when placed on the bed plate 13 the overhanging parts approach, at one end of each of the supporting 65 members 14, the bed plate 13, that is, one end of the overhanging part is located higher with respect to the bed plate 13 than the other end. A plate 15 is placed on the overhanging supporting parts 14 and preferably extends to the outer edges of the supporting parts 14 which preferably converge toward the needles. A plate 16 is also supported by the supporting members 14 and in spaced relation with respect to the plate 15. 70 The edges of the plates 15 and 16 are located in parallel relation and the leading edges, with respect to the needles and the movement of the material to the needles, are spaced apart considerably more than the following edges. The plates 15 and 16 are 75 fluted or corrugated and the corrugations converge from the leading edges toward their following edges and deepen as they approach the following edges. The corrugations 17 of the plates are located in parallel relation, that is, the corrugations of one plate fit the corrugations in the other plate and so as to leave between the corrugations 80 spaces substantially the same taken along any line or vertical plane parallel to the leading edges of the plates, but as the corrugated portions approach each other they become more pronounced. The side edges of 85 each of the plates preferably approach each other as the corrugations become more pronounced. Near the leading edges the plates are flat and their surfaces are plane while in the following edges the plates are deeply corrugated. The corrugations at the following edges of the plates are formed in 90 such a way that the concave curvature of the portions of the plates, looking from above the plates, is much sharper than the convex curvature of the other portions of 95 the plates. The relative positions of the plates are secured by means of the thumb 100

105

110

screws 18 and suitable spacing members such as the short sleeves or collars 19. The screws 18 may be threaded into the supporting members 14 while the spacing members 19 are located intermediate the plates 15 and 16.

The presser feet 20 of the machine are located in proximity to the delivery end of the guide and compressing member 12. 10 They are located in line with the concave portions of the guide member and thus the needles 2 that coat with the presser feet sew their threads through the material that is delivered from the guide member at these 15 points. The plates 15 and 16 may be provided with notches 21 in which the presser feet 20 and the needles 2 may operate and thus they will be located within the vertical plane of the following edges of the plates 15 20 and 16.

The material is fed through or drawn through the guide and compressing member 12, and beneath the presser feet 20 while it is being operated upon by the needles 2. 25 In forming the cushion, a fabric, such as heavy muslin or canvas 22, is placed on the bed plate or shelf 13 and suitable filling material such as cotton or felt or cushion material 23 is placed on the fabric 22. These 30 are placed between the supporting members 14 which form also guides for the fabric 22 and cushion material 23, as they are drawn through the machine. The plate 15 is placed on the supporting members 14 35 above the cushion material 23 and a suitable covering material such as imitation leather or leather 24 is placed on the plate 15. The plate 16 is then placed on or above the covering material 24. The parts are 40 then secured together by means of the thumb screws or bolts 18. The material 23 is thus compressed at the sharply curved portions or parts of the following edges of the plates while the material intermediate these points 45 is allowed to remain loose, that is, substantially normal though it may be compressed somewhat. Also the covering material 24 is gathered along the following edges of the plates, that is, is made to conform to the corrugations. The material is started through 50 the machine beneath the presser feet 20, and the needles 2, and is fed and drawn through the machine and while thus being operated upon, the cushion material 23 is compressed as it approaches the following 55 edges of the plates and the covering material 24 is gathered, that is, made to conform to the corrugated shape and as the material passes beneath the needles they are sewed 60 to the fabric 22 whereby the parts are secured in their relative positions.

Behind the needles is located a presser-bar 26 that extends across the machine and above the material. It is connected by parallel links 27 to the frame of the machine.

The presser-bar 26 is given reciprocatory movements in crosswise direction by means of the rod 28 which is connected to a cam strap 29 operated upon by a suitable cam located on the cam shaft 30. The shaft 30 70 is rotated by means of the shaft 31 which is connected to the shaft 9 by the belt 32 which moves over and connects the pulley wheels 33, one located on the shaft 9 and the other on the shaft 31. Rotation of the shaft 30 causes the presser-bar 26 to move down against the top of the corrugations formed in the material when they have been secured together and delivered from the guide member 12 and so as to carry the tops of the 80 corrugations over to one side and fold them down in the manner illustrated in Fig. 6, which is a sectional view of the material looking from behind the machine. When the elevated portions of the cushion as delivered from the needles have thus been folded down, so as to cause an overlapping of parts of the covering material 24 by the operation of the presser-bar 26 the cushion is passed beneath a roller 34 which not only operates to make more perfect the folds but also operates to draw the material through the guide and compressor member 12 and beneath the needles 2. The roller 34 is operated by any suitable means such as the 85 worm gears 35 which are in turn operated by the shaft 31. The folding down of the covering material covers the row of stitches used in sewing the parts together. If the folding of the parts between the rows of 90 stitches is omitted the parts will however, in use and even in stretching the material over the springs, flatten slightly and spread so as to close over the stitches and then practically cover the stitches. As the material is delivered from beneath the roller 34 it may be rolled up by any suitable means 95 and subsequently may be cut in suitable lengths and widths according to the sizes of the seats or backs or other parts that are to 100 be upholstered.

I claim,—

1. In combination with a gang sewing machine, a guide member having a pair of plates the plates having converging corrugations and located in spaced relation with respect to each other, a bed plate for supporting the plates, the lower plate located in spaced relation with respect to the bed plate.

2. In combination with a gang sewing machine, means for compressing a cushion material along definite lines in line with the needles of the sewing machine, and means for directing a sheet material over the compressed cushion material.

3. In combination with a gang sewing machine, means for compressing a cushion material along definite lines in line with the needles of the sewing machine, means for 130

directing a sheet material over the compressed cushion material, and gathering the sheet material to cause it to conform to the sinuous surface of the cushion material produced by compressing the cushion material along definite lines.

4. In combination with a gang sewing machine, a bed plate, a pair of plates having converging corrugations located in spaced relation to each other and also with respect to the bed plate and operating to compress a cushion material passing beneath the plates and to feed a sheet material over the cushion material and to gather the sheet material to cause it to conform to the surface produced by the pressure of the lower plate on the cushion material, the needles of the gang machine being located in line with the lowermost parts of the corrugations of the plates.
5. In combination with a gang sewing machine, a guide member having a pair of

plates the plates having converging corrugations and located in spaced relation with respect to each other, a bed plate for supporting the plates, the lower plate located 25 in an inclined position with respect to the bed plate, the lower parts of the corrugations located in a line with the needles of the gang machine.

6. In combination with a gang sewing machine, means for compressing a cushion material along definite lines in line with the needles of the sewing machine and means for directing a sheet material over the compressed cushion material, means for folding 35 by lateral movement the portions of the sheet material intermediate the lines of sewing.

In testimony whereof I have hereunto signed my name to this specification.

ADOLPH H. LICHTER.
